UNITED STATES PATENT OFFICE.

MARKUS KLEINBERGER, OF NEW YORK, N. Y.

DESIGN FOR A DRESS-CHART.

SPECIFICATION forming part of Design No. 34,854, dated July 23, 1901.

Application filed May 15, 1901. Serial No. 60,406. Term of patent 7 years.

To all whom it may concern:

Be it known that I, MARKUS KLEINBERGER, a citizen of the United States, and a resident of New York city, county and State of New York, have invented a new and original Design for a Dress-Chart, of which the following is a specification, reference being had to the accompanying drawing, which represents a face view of my newly-designed dress-chart.

The essential feature of the design resides in providing the dress-chart with a series of truncated sector-shaped gores which extend from edge to edge across the chart, the gores being subdivided and intersected by curved transverse lines which are eccentric to the lower edge of the chart.

Referring to the drawing, A represents the chart, having the form substantially of a truncated sector with the curved upper edge *a*, an eccentric lower edge *b*, a diverging edge *d*, and a straight edge *c*, extending at right angles to and connecting the edges *a* and *b*.

From the upper edge *a* to the lower edge *b* are drawn a number of radial lines *g h i j k l m n o*, arranged singly and in groups of two and three, which form a series of truncated sector-shaped gores across the chart. The gores are subdivided and intersected near their upper edges by a transverse line *e* and near their lower edges by a series of transverse eccentric lines *f*, which form a number of sections that taper from the lower edge *b* to the upper edge *a* of the chart.

What I claim is—

The design for a dress-chart, substantially as shown and described.

Signed by me at New York city, county and State of New York, this 10th day of May, 1901.

MARKUS KLEINBERGER.
